CA 143430 S 11/2012

OTHER PUBLICATIONS

Communication dated Jan. 10, 2019, from the Canadian Intellectual Property Office in counterpart application No. 174811.

Primary Examiner — Daniel J Domino

(74) Attorney, Agent, or Firm — Arent Fox LLP

CLAIM

The ornamental design for a display screen with graphical user interface, as shown and described.

DESCRIPTION

The FIGURE is a front view of a display screen with graphical user interface showing our new design.

The two outermost broken lines showing an electronic device illustrate environmental subject matter, whereas the broken lines showing elements of the graphical user interface illustrate portions of the article. No subject matter depicted in broken lines form part of the claimed design.
